SPRINKLER HEAD

Delbert F. Dunham, Tujunga, Calif.

Application October 13, 1944, Serial No. 558,562

14 Claims. (Cl. 299—71)

1

This invention relates to and has for an object the provision of an improved sprinkler head adapted to be connected with a source of water supply so as to distribute water over a surface within the extremes of a predetermined arc, and to the extent, if desired, of a complete circle, together with means under the influence of the jet of water for automatically reversing the direction of movement of the sprinkler head following the completion of a movement in one direction, or continuing the movement without reversal in the said one direction.

I am aware that other sprinkler heads have been heretofore used for the accomplishment of a similar purpose, but in at least those devices of which I have knowledge, weights, springs and other means have been employed to obtain a step-by-step rotation of the head and to reverse the rotative direction of the head, whereas I have devised a head which relies upon a novel arrangement of parts under the influence of water pressure for such purpose.

It is an object of this invention to provide a sprinkler head which is provided with laterally inclined wings extended from opposite sides of the central vane which, regardless of the position of the central vane or impulse member, will be subject to the water pressure applied from the jet and will occasion the reversal of the impulse member when the impulse member reaches its opposite extremes of movement.

Another object is to provide an oscillatable regulator pivotally mounted on the head and adapted to be intermittently engaged by a portion of the impulse member as the impulse member is swung to opposite extremes of its movement and which, due to the successive impacts of the impulse member against the head will gradually and progressively move the head in a step-by-step movement between its extremes of adjustment and effect its reversal when the head has reached its extremes of movement.

A further object is to provide on the stationary fixture at least a pair of limiting elements which are selectively adjustable for predetermining the swing of the impulse member in opposite directions throughout a desired range of arc.

It may be understood that in my improvement I have provided a sprinkler head which essentially includes a stationary fixture adapted for connection with a source of water supply, a water jet rotatably or oscillatably mounted thereon, means for limiting the rotative movement of the water jet in opposite directions, an impulse member which is rotatable both on and with and un-

2

der the influence of the water jet, and a regulator which is operated by impact of the impulse member therewith, all of which elements combine to produce a progressively rotative movement of the sprinkler throughout a predetermined arc or circle, as in a step-to-step movement, either continuously in a given direction or alternately in reverse directions, due to the application of water pressure to the impulse member.

Other objects may appear as the description of my invention progresses.

I have shown a preferred embodiment of my invention in the accompanying drawing, subject to modification, within the scope of the appended claims, without departing from the spirit of the invention. In said drawing:

Fig. 1 is a side elevation of my sprinkler head;

Fig. 2 is an elevation of the same as seen at right angles to Fig. 1;

Fig. 3 is a sectional elevation of the same on line 3—3, of Fig. 2; and

Figs. 4, 5 and 6 are top plan views showing the water jet, the impulse member and the regulator in different positions during the operation of the device.

Briefly described and as shown in the drawing a sprinkler head embodying my improvements includes a stationary fixture 1 which is threaded at 2 for attachment to underground or surface water service pipes (not shown) such as are employed for sprinkling lawns, a water jet member or head 3 rotatably mounted on fixture 1, as shown in Fig. 3 and hereinafter described, an impulse member 4 rotatably mounted on member 3, a regulator 5 oscillatably mounted on member 3, and a pair of limiting elements 6 and 7 adjustably mounted on fixture 1.

Member 3 has a body 8 overlying the upper cylindrical portion 9 of member 1 and a hollow stem 10 having a passage 11 therethrough screwed into body 8. A head 12 is formed on stem 10 below threaded portion 2, a gasket 13 being held between portions 2 and 12 for providing a leak-proof joint and yet permitting the rotation of member 3 on member 1.

Member 3 has a laterally extended and, if desirable, upwardly inclined nozzle 14 with a passage 14' therein and communicating with the passage 11 so that water from a source may be discharged in the form of a jet from said nozzle in a sprinkling operation. Member 3 forms a support for the impulse member 4 and for such purpose has an upstanding stud 15 threaded into the top of body 8 and extended through the hub 16 of member 4 and having nuts 17 on the upper

end thereof above member 4 for holding the impulse member in operative position.

Member 3 also has a radial extension 18 which is adapted to support the regulator 5 in oscillatable position on the upper side thereof as by means of a pin 19 extended through extension 18 and held by means of a bushing 20 press fitted into a counterbore of said extension (See Fig. 3). Impulse member 4 has diametrically disposed arms 4a and 4b which have, respectively, a downwardly slanting vane 21 and a depending boss 22, vane 21 being movably disposed relative to the nozzle 14 and boss 22 being movable over and relative to regulator 5. Arm 4a of impulse member 4 also has a pair of laterally inclined wings 4c and 4d (Fig. 2) which flare outwardly and incline downwardly to a uniform extent on opposite sides of vane 21. Thus, regardless of whether the vane 21 is positioned centrally or to one or the other side of the center of the nozzle 14, the force of the water jet from said nozzle when directed against the lower surfaces of the inclined wings will tend to correspondingly move the impulse member in opposite directions to a predetermined extent and the head 3 in a given direction until its movement is stopped by one of the limiting elements 6 or 7, under the control, however, of the regulator 5.

When the impulse member 4 and the head 3 have progressed in a given direction, in a step-by-step movement as later explained, together about the axis of the body 1 and throughout the extent of a predetermined arc, the element 6 or 7, as the case may be, is engaged by a rod 23 which depends from the center of one edge of the regulator 5 whereupon rotative movement of the member 3 and the impulse member 4 in one direction is stopped and successive swinging movements of the impulse member which are occasioned by the force of water against the opposed wing 4c or 4d and vane 21 occasions the reverse movement of the member 3 and impulse member 4 in the manner I will now explain.

Member 5 is at all times free to swing in one or the other direction on its axis 19 and it includes a flat plate 24 with upstanding pins 25 and 25a adjacent its extremities and of such height as to engage and limit the movement of impulse member 4 to a predetermined arc whereby the wings 4c and 4d are alternately under the influence of the water jet. Also member 5 has a pair of shorter upstanding pins 26 and 26a inwardly of pins 25 and 25a, respectively, adapted to engage the peripheral surface of the depending portion 22 at times. The outermost portion of the periphery of portion 22 of the impulse member is cut away as at 27 so that when the regulator is in alternate positions relative to the member 4, the portion 22 may swing free of pin 26 or 26a, as the case may be.

The extent of rotation of members 3, 4 and 5 about the axis of stationary fixture 1, in any direction, may be limited by the stop elements 6 and 7 carried on the stationary fixture 1. Said elements 6 and 7 have one or more turns, as at 6a and 7a, tightly wound around the portion 9 of fixture 1 so as to be frictionally held in adjusted positions thereon and radially extended portions 6b and 7b, respectively, projected into the path of the depending rod 23 from member 5. Thus, the portions 6b and 7b may be turned to a desired extent around the fixture 1 for limiting the swinging of the members 3, 4 and 5 to a desired extent, even to the extent, when portions 6b and 7b are close together or superposed, of permitting the oscil-

lations of the head to an operable extent of 360 degrees for the purpose of sprinkling a large area of a lawn.

Thus, from the foregoing description and the illustration of my sprinkler head in the drawing it will be apparent that there are three separate cooperating movements of the head and the elements which adapt the device for adequately sprinkling water over an expanse of lawn. Such movements may be defined as follows: first, the natural spread of a stream of water issuing from the jet or nozzle 14; second, the sweep of the impulse member 4 which diffuses the water over a restricted area; and third, the progressive movement of the head circularly about the axis of the stationary fixture 1 within the range of a predetermined arc, depending upon the adjustment of the limiting elements 6 and 7.

Due to the force of the stream of water issuing from the nozzle 14 the vane 21 will be moved to one or the other side of the nozzle and in the absence of the wings 4c and 4d, unless otherwise actuated, could not swing in a reverse direction.

The regulator 5 serves to limit the swinging of the vane 21 and the wings 4c and 4d to extremes of movement always within the influence of the water jet and, due to the angularity and disposition of the wings, the force of the water stream is directed against one of the wings so as to effect a return stroke of the impulse member in the direction of the then operative wing, after which movement the impulse member is moved to an opposite extreme and the other wing is effective for occasioning a reverse stroke.

The regulator 5 with its upstanding pins 25 and 25a and pins 26 and 26a thereon limits the sweep of the impulse member 4, and at the same time the impact of said impulse member with pins 26 and 26a, or either of them, gradually and progressively swings the head 3 on its pivot 10 in a step-by-step movement until stopped by engagement of rod 23 with limiting element 6 or 7. Successive impacts of the impulse member with the pins 26 and 26a, as the case may be, tend to rotate the water jet member 3 in one or the other direction to an extent permitted by the adjustment of the limiting elements 6 or 7. For instance, as shown in Fig. 4, when rod 23 of regulator 5 engages limiting element 7b the head will have rotated on member 1 as far as possible in a clockwise direction and it will now begin a counter-clockwise movement in the direction of its other extreme of movement as defined by the position of the limiting element 6b. At such point in the operation of the device, it will be remembered that the member 4 is still oscillating and the successive impacts of the portion 22 on pin 26 will gradually swing the head in a counter-clockwise direction, as shown in Fig. 5, to an opposite extreme of movement, during which time, of course the members 3 and 4 have been moved progressively, in a step-by-step movement about the axis of stationary fixture 1, and such progress of member 3 will continue until again stopped by engagement of rod 23 with the limiting element 6b, at which time a reverse movement of the member 3 will ensue.

After the first impact of the stream of water on vane 21 has caused the head to knock the regulator 5 into a position in which one pair of pins 25, 26 or 25a, 26a is located closer to the axis of rotation of the head than the other pair of pins, the rotation of the head in a step-by-step manner is caused by the impact of the depending portion 22 to greater force against the pin

26 or 26a nearer the axis than against the pin 25 or 25a struck on the reverse stroke. When the movement of the head in each swing is arrested by the impact of the depending member 22 with a pin, the force of the water against the upward and inwardly sloping vane 4c, 4d is sufficient to start the head swinging in the opposite direction and bring the vertical vane into the stream of water and past the center line thereof, whereupon the extra force of the water acting on the vertical vane on one side will accelerate movement of the head in the direction in which it is already moving until the downward slope of the vane following will cause the movement to be slowed down, but to a lesser degree on the shorter swing than on the longer swing. The force of the impact of the depending part 22 on a pin is therefore greater at one end of the swing of the head 3 than at the other resulting in turning the head in a series of jerks in one direction until rod 23 strikes the stop 6b or 7b. Since the regulator 5 in its operative position carries the rod 23 slightly ahead of the pivotal point of the regulator, engagement of the rod with the stop will swing the regulator in the opposite direction so that the opposite pair of pins will be brought nearer the axis of rotation of the head resulting in the reverse movement of the head 3 until the other stop is struck by the rod 23.

It should be distinctly understood that the operation of the impulse member continues as long as water is issued from the nozzle 14 and regardless of the relative position of the member 3 with regard to stationary fixture 1. When the rotative movement of member 3 is stopped by engagement of the rod 23 with one of the limiting elements 6 or 7, the force of the water is exerted on the member 4, through wings 4c and 4d, to return said member 4 to an opposite extreme of movement. This is occasioned by the fact that the force which is applied to vane 21 and the wing 4c or 4d, as the case may be, then is applied to said vane and an opposite wing for reversely moving the same.

It may be noted that in my sprinkler head the impulse member 4 is mounted coaxially with members 1 and 3 while the regulator 5 is mounted on an axis off-set from the axis of the impulse member 4 and member 3.

Hence, it may be understood that as herein disclosed I have provided a rotative sprinkler head embodying a stationary fixture attachable to a water service pipe, a water nozzle rotatable thereon, adjustable means for limiting the effective arc of said nozzle, an impulse member rotatable on as well as with said nozzle and having means disposed adjacent the nozzle adapted to be influenced by a stream of water issuing therefrom for alternately moving the impulse member in opposite directions, and a regulator cooperating with said impulse member for limiting the sweep of the impulse member during the rotation of said member about the axis of the supporting fixture.

I claim:

1. A rotary sprinkler comprising: a stationary fixture arranged for connection with a source of water supply, a nozzle rotatable thereon, an impulse member rotatable both on and with said nozzle and having means disposed adjacent said nozzle and under the influence of the stream of water issuable from said nozzle including a central vane and inclined wings outwardly of opposite sides of said vane for oscillating the impulse member so as to direct the stream of water

over a predetermined area, and cooperating means on said fixture and associated with said impulse member for limiting the movement of the nozzle and the impulse member together in the opposite directions and to a predetermined extent.

2. A rotary sprinkler comprising: a stationary fixture of hollow cross section adapted for connection with a source of water supply, a head rotatable thereon and provided with a radially disposed water jet, and an impulse member oscillatably mounted on said head and formed with a vertically disposed vane and laterally inclined wings extending from opposite sides of said vane

15 and bent downwardly at their extremities, said impulse member being bodily oscillatable to permit the swinging of said vane and wings to and fro relative to said water jet due to the influence of a single stream of water issuable from said jet.

20 3. A rotary sprinkler as characterized in claim 2 including: a regulator pivotally carried on said head and having an axis paralleling that of the impulse member and having portions disposed in 25 the path of a portion of the impulse member for limiting the sweep of the impulse member during the rotation of the impulse member and head relative to the support.

4. A rotary sprinkler as characterized in claim 30 2 including: a regulator pivotally carried on said head and having an axis off-set from that of the impulse member and having portions disposed in the path of a portion of the impulse member for limiting the sweep of the impulse member during 35 the rotation of the impulse member and head relative to the support, a pair of limiting elements adjustable rotatively on said stationary support, and means carried by said regulator for engagement alternately with said pair of limiting elements 40 for arresting the rotative movement of the impulse member and jet at the extremes of predetermined arcs of movement.

5. A rotary sprinkler comprising: a fixture attachable to a source of water supply, a head rotatable thereon and provided with a water jet, an impulse member coaxially mounted on said head above said jet for common rotation with the head on said fixture and independently oscillatable on said head, and a regulator pivotally 45 carried by said head and oscillatable on an axis radially spaced from and paralleling the axis of the head and having spaced elements disposed in the path of the impulse member for limiting the movement of the impulse member in opposite 50 directions, said impulse member having a vane disposed edgewise adjacent the water jet and solely under the influence of a stream of water issuable from said jet.

6. A rotary sprinkler comprising: a fixture attachable to a source of water supply, a head rotatable thereon and provided with a water jet, an impulse member coaxially mounted on said head for common rotation with the head on said fixture and independently oscillatable on said head, and a regulator pivotally carried by said head and oscillatable on an axis off-set from the axis of the head and having spaced elements disposed in the path of the impulse member for limiting the movement of the impulse member in opposite directions, said impulse member having a vane disposed edgewise adjacent the water jet and solely under the influence of a stream of water issuable from said jet, and laterally disposed inclined wings extended from opposite sides 70 of said vane against which the water from said jet

impinges so as to alternately move the impulse member in different directions.

7. A rotary sprinkler as characterized in claim 5 including: a pair of frictionally adjustable limiting elements carried by said fixture for arresting the rotative movement of the head and impulse member at predetermined points, and means carried by said regulator alternately engageable with said pair of limiting elements, said impulse member being arranged for continuous oscillation regardless of the stoppage or the rotative movement of the head.

8. A rotary sprinkler comprising: a stationary fixture adapted for connection with a source of water supply, a head freely rotatable within predetermined limits on said fixture and having a radially extended nozzle from which a stream of water is issuable during the rotation of the head, an impulse member coaxially mounted on said head for oscillation within predetermined limits and also rotatable with said head, said impulse member having a central vane and wings laterally inclined therefrom which are together movable in an arc adjacent said nozzle and under the influence of a jet of water issuable from said nozzle, for providing a forward and backward sweep of the stream of water during the progressive rotative movement of the nozzle and stream about the axis of said fixture.

9. A rotary sprinkler as characterized in claim 8 including: a regulator having an axis off-set from but paralleling the axis of the head and provided with spaced elements disposed in the path of a portion of the impulse member for limiting the oscillation of the impulse member.

10. A rotary sprinkler as characterized in claim 8 including: means adjustably carried by said fixture for arresting the rotative movement of the impulse member and head, and means carried by the regulator and engageable with said arresting means, whereby at the completion of a movement of the impulse member and head in a given direction a reverse movement will be instituted.

11. A rotary sprinkler comprising: a supporting fixture adapted for connection with a source of water supply, a head rotatable on said fixture, a nozzle on said head, an impulse member coaxially mounted on said head for oscillation in an arc of less extent than that of the head and including a diametrically disposed bar having a vane and a pair of oppositely inclined wings at one end thereof, a regulator oscillatably mounted on said head in a position off-set from the impulse member and having spaced stop devices extended upwardly therefrom and engageable with the rear end of said impulse member for arresting the oscillative movement of the impulse member alternately in opposite directions, the vane and wings of the impulse member being movable relative to the nozzle solely under the influence of a single stream of water issuable from the nozzle.

12. A rotary sprinkler as characterized in claim 11 including: means carried by said head and by said fixture cooperatively arranged for arresting the rotative movement of the head and the impulse member at opposite extremes of their rotative arc, said last mentioned arresting means including rotatably adjustable elements carried by

the fixture and an element carried by and depending from said regulator and engageable with the rotatable elements.

13. A sprinkler comprising: a fixture attachable to a water service pipe, a head rotatable thereon and having a vertical passage therein for the passage of water therethrough, an impulse member rotatable both with and independently of the head on an axis coaxial with that of the head, a jet nozzle in communication with said vertical passage, a regulator pivotally mounted on a vertical axis at a point diametrically opposite the nozzle and provided with spaced upstanding stops disposed in the path of a rear portion of the impulse member for limiting the movement of the impulse member in opposite directions relative to the head, said impulse member having a forward extension formed with a vane disposed adjacent the nozzle and laterally inclined wings on opposite sides of said vane, whereby a jet of water issuing from said nozzle will impinge on and influence the rotation movement of the impulse member on the head to an extent permitted by said stops and successive impacts between the rear portion of the impulse member and stops alternately will occasion rotative movement of the head on the fixture and thus spread the water over a predetermined area.

14. A sprinkler comprising: a fixture attachable to a water service pipe, a head rotatable thereon and having a vertical passage therein for the passage of water therethrough, an impulse member rotatable both with and independently of the head on an axis coaxial with that of the head, a jet nozzle in communication with said vertical passage, a regulator pivotally mounted on a vertical axis at a point diametrically opposite the nozzle and provided with spaced upstanding stops disposed in the path of a rear portion of the impulse member for limiting the movement of the impulse member in opposite directions relative to the head, said impulse member having a forward extension formed with a vane disposed adjacent the nozzle and laterally inclined wings on opposite sides of said vane, whereby a jet of water issuing from said nozzle will impinge on and influence the rotation movement of the impulse member on the head to an extent permitted by said stops and successive impacts between the rear portion of the impulse member and stops alternately will occasion rotative movement of the head on the fixture and thus spread the water over a predetermined area, a pair of stops carried by the fixture which are separately adjustable rotatably about the common axis of the head and impulse member, and a member depending from said regulator to a position of engagement with said last mentioned stops for limiting the rotative movement of the head.
